[57] CLAIM

The ornamental design for a wheel, as shown and described.

DESCRIPTION

FIG. 1 is a perspective view of a wheel showing my new design;

FIG. 2 is a front elevational view thereof;

FIG. 3 is a left-side elevational view thereof, the right side being a mirror image of the left side; and,

FIG. 4 is a cross-sectional view thereof taken along the line 4—4 in FIG. 2.

The broken line disclosure in FIGS. 1-4 is for illustrative purposes only and forms no part of the claimed design.

The rear of the wheel forms no part of the claimed design.
